FLAT RIB KNITTING MACHINE

Woldemar Heinitz, Chemnitz, Germany, assignor
to Schubert & Salzer Maschinenfabrik Aktien-
gesellschaft, Chemnitz, Germany

Application December 10, 1935, Serial No. 53,811
In Germany December 10, 1934

1 Claim. (Cl. 66—101)

The present invention relates to flat rib knitting machines for the manufacture of tuck loops or tuck wrap loops.

Tuck loops are obtained hitherto upon flat rib knitting machines by the fact, that, by means of presser plates, presser combs or the like, a number of frame needles are, according to rows, not pressed or prevented from moving into the range of the presser. Consequently, this tuck patterning was limited to repetition according to rows.

Tuck wrap loops are obtained hitherto upon flat rib knitting machines by the fact, that the thread or wrap guides of the Jacquard apparatus each present their thread to at least two frame needles which thread is then sunk without a ground thread being presented to the frame needles, whereupon the needles, carrying this thread, are pressed by a common presser, so that closed continuous rows of tuck wrap loops are formed.

The present invention allows an increase of the patterning possibility of the tuck loops as well as the tuck wrap loops, as individual tuck loops may also be formed as tuck wrap loops at any desired points of the row of loops.

To obtain the desired object, special press instruments are provided which, by means of a special Jacquard roller or by means of the Jacquard roller already present for producing plating wrap loops, are brought into or withdrawn from the range of the heads of the frame needles. The special press instruments are then by the general presser pressed against the frame needles, whereby by the frame needles, not pressed under pattern control, tuck loops according to pattern are obtained, and whereby pressing under pattern control of the frame needles carrying thread is obtained when forming tuck wrap loops, so that tuck loops and tuck wrap loops respectively are produced.

In this manner, tops or rib tops may be formed in the row of loops of which any desired tuck patterns may be obtained, or any desired tuck wrap patterns may be produced in the row of loops if no tuck patterns are formed. The tuck wrap patterns may, furthermore, be combined with wrap loops. These different kinds of patterns, i. e., tuck patterns, tuck wrap patterns or plating wrap patterns may then alternate successively and among one another respectively in the direction of the wales.

In plain rows of loops in which no tuck patterns and no tuck wrap patterns are formed, i. e., no press instruments are shifted into the

range of the heads of the frame needles, all the frame needles are pressed by the general presser. For this purpose a special cam is provided adapted to impart the greater movement to the presser which for this purpose is necessary. All the press instruments could, however, be brought into the range of the heads of the frame needles in plain rows of loops also.

The essence of the invention is not altered, if instead of the press instruments individually movable frame needles are, under pattern control, brought into or withdrawn from the range of the presser by means of the Jacquard apparatus.

It is also of no importance, whether the Jacquard apparatus is arranged for a single group of thread or wrap guides or a Jacquard apparatus with a plurality of groups of such guides is used.

In the accompanying drawing some embodiments of the invention are shown by way of example.

In this drawing:

Fig. 1 is a side elevation, partly in section, of as much of a flat rib knitting machine as is necessary for explaining the construction and operation of the arrangement according to the invention,

Fig. 2 is a broken away diagrammatic side elevation showing the individual parts of the device according to the invention in the position they occupy in the moment of pressing,

Fig. 3 is a perspective view of the press instruments also in the position they occupy in the moment of pressing,

Fig. 4 is a view of a portion of the Jacquard card for the press instruments,

Fig. 5 shows a double Jacquard apparatus with several groups of thread or wrap guides, showing the guides and the mechanisms acting on them in the inoperative position,

Fig. 6 is a view of a portion of the Jacquard card used in combination with the apparatus shown in Fig. 5, and

Fig. 7 is a diagrammatic side elevation of a construction according to which the individually movable frame needles are, under pattern control, brought into and out of the range of the presser.

In all figures, one bank of needles only is shown, the other bank being omitted for the sake of simplicity.

In the construction shown in Figs. 1—4, 1 are the frame needles and 2 the thread or wrap guides. These guides are operated by the Jac-

guard card 4 led around the Jacquard roller 3. 5 are the jack sinkers and 6 is the general presser in the range of which the press instruments 8, 8' may be brought which are guided in bearings 5. The press instruments 8, 8' are, by means of springs 9, held in a withdrawn position and may be brought into operative position by a Jacquard card 11 led around a special Jacquard roller 10.

Fig. 2 shows a press instrument, the general 10 presser, the frame needle and the jack sinker in the position they occupy in the moment of pressing; Fig. 3 illustrates in a perspective view the same position of the individual parts.

The thread or wrap guides 2 are actuated, in a 15 well known manner, by a Jacquard card 4 led around the Jacquard roller 3.

If tuck loops are to be formed upon the frame 20 needles 1, the portion of the press instruments proper of the device operates only. By the Jacquard card 11 (Fig. 4), led around the special 25 Jacquard roller 10, the press instruments 8, 8' are brought into the operative position. These press instruments are, by the general presser 6, pressed against the frame needles 1, so that plain loops are formed at these needles. On the 30 needles, not pressed by the press instruments, tuck loops under pattern control are produced.

If, however, tuck wrap loops are to be formed 35 upon the frame needles 1 in which case no ground thread is presented, the wrap or thread guide apparatus as well as the press instruments, i. e., the whole device, are required. The frame needles 1 are fed with thread by the thread guides 2. By a Jacquard card 11 (Fig. 4), led around 40 the special Jacquard roller 10, press instruments 8, 8' are brought into operative position. These press instruments are again pressed against the frame needles 1 by means of the general presser 6. By pressing the needles, carrying thread, tuck 45 wrap loops under pattern control are obtained.

According to Fig. 5 a double Jacquard apparatus with several groups of thread guides is used. It has been supposed, that two groups of thread guides are provided. Accordingly the Jacquard 50 card 18, led around the Jacquard roller 3, must be provided with two rows of perforations for the two groups of thread guides. It has been supposed, that also the press instruments 8, 8' are actuated by the same Jacquard card. The press instruments 8, 8' are actuated by thrust heads 12, 12' provided at the ends of arms 13 of double-armed levers 13, 14 which are pivotally mounted upon a shaft 15. The other arms 14 of the double-armed levers 13, 14 cooperate with 55 slides 16 actuated by the Jacquard card 18. As

shown in Fig. 6, the Jacquard card 18 is provided not only with the two rows of perforations necessary for actuating the two groups of thread guides, but also with a third row of perforations.

If the Jacquard roller 3 is moved against the 5 thread guides 2, the latter are, under pattern control, brought into the operative position. If the Jacquard roller 3 is moved in the opposite direction, the Jacquard card acts upon the slides 16, so that, as long as perforations are not present in the third row, the double-armed levers 13, 14 are shifted and the press instruments 8 acted upon by the thrust head 12 (Fig. 5), are brought into the range of the frame needles 1. If, however, a perforation is present in the Jacquard 15 card, the slide 16 enters this perforation, so that the double-armed lever 13, 14 remains in its position and the thrust head 12' (Fig. 5) does not shift its press instrument 8.

If a simple thread or wrap guide apparatus is 20 used as shown in Fig. 1, the thread guides may be actuated by the Jacquard apparatus acting upon the press instruments, instead of using a special Jacquard apparatus. Such a construction of the double thread or wrap guide apparatus is shown in Fig. 5. The Jacquard card must then be provided with two rows of perforations one of which acts upon the thread guides on movement of the Jacquard roller against the thread guides, whereas, by a movement of the 25 Jacquard roller in the opposite direction, this roller acts with its second row of perforations upon the slides actuating the press instruments.

According to the construction shown in Fig. 7, 30 it has been supposed, that the frame needles 1 are individually movable. The arms 28 of double-armed levers 28, 29 engage the feet of the frame needles 1. The double-armed levers 28, 29 are pivotally mounted upon a shaft 30. The 35 other arms 29 of the double-armed levers 28, 29 are actuated by the slides 31, which are influenced by a card 33 led around the Jacquard roller 32. By this arrangement also the individually movable frame needles may, under pattern control, 40 be brought into and withdrawn from the range of the presser 6.

What I claim is:

A flat knitting machine substantially for the purpose set forth, comprising frame needles, a 50 general presser, press instruments, wrap guides and a horizontally movable Jacquard roller acting upon said press instruments and upon said wrap guides.

WOLDEMAR HEINITZ. 55
